(57) **CLAIM**

The ornamental design for a windscreens wiper arm adjusting tool, as shown and described.

DESCRIPTION

FIG. 1 is a front elevational view of a windscreens wiper arm adjusting tool showing my new design;

FIG. 2 is a top plan view thereof;

FIG. 3 is a rear elevational view thereof;

FIG. 4 is a bottom plan view thereof; and,

FIG. 5 is a left side elevational view thereof, it being understood that the opposite side is a mirror image thereof.
